UNITED STATES PATENT OFFICE

2,546,667

DERAIL

Stanley W. Hayes, Richmond, Ind., assignor to
 Hayes Track Appliance Company, Richmond,
 Ind., a corporation of Indiana

Application June 14, 1944, Serial No. 540,244

15 Claims. (Cl. 246—163)

1

The present invention relates to derails and particularly to derail guide boxes and has for its primary object the provision of a new and improved derail and derail guide box which may be constructed readily and economically.

Another object of the present invention is the provision of a new and improved derail guide box which is adaptable exactly to fit any height of rail without requiring adzing of the ties under the rail or guide box or shimming at these points.

Another object of the present invention is the provision of a new and improved derail guide box which is adaptable to any system of track construction, i. e., systems in which the rails are supported either level or canted.

A further object of the present invention is the provision of a new and improved derail guide box which may be readily constructed to be of a desired width, whereby it may be readily and accurately installed no matter what the distance between ties.

Another object of the present invention is the provision of a new and improved derail which will fit any kind of track construction and which may be installed with the assurance that it will fit accurately.

Another object of the present invention is the provision of a new and improved sliding derail adaptable to rails supported on level or canted tie plates and wherein the movement of the derail block on and off the rail has the same relation to the rail as though both the rail and derail guide box were flat upon the ties.

A further object of the present invention is the provision of a new and improved derail guide box which may be fabricated readily from a number of parts which can be cut, forged and welded to form the box or in which the parts may be made as castings, if desired, and assembled as by welding.

Another object of the present invention is to provide a new and improved derail guide box for sliding derails wherein the vertical side plates together with the derail block supporting and guiding structure are made as castings, thereby to avoid the considerable work required to fabricate the vertical side plates from steel plate.

A further object of the present invention is to provide a new and improved derail guide box having a standard shell including front and rear cross braces and vertical side plates which will fit the highest rail of a series of rails without change and which can be made to fit lower rails by trimming off portions of the front brace and (preferably) side plates, whereby the derail guide

2

box may then be supported upon the ties by horizontal tie flanges secured to the side plates at the proper heights.

Another object of the present invention is the provision of a new and improved guide box having horizontal tie flanges for securing the box to the ties, which tie flanges extend underneath and beyond the rail to provide a unitary guide box tie flange and tie plates, the tie flange also being provided with braces for engaging the far side of the rail and being apertured to receive securing spikes bearing thereagainst, thereby to provide a secure installation.

Other objects and advantages of the present invention will become apparent from the ensuing description, in the course of which reference is had to the accompanying drawings, in which:

Fig. 1 is a top plan view, partly broken away, of a sliding derail constructed in accordance with the present invention, the derail being shown attached to a pair of adjacent ties and with the derail block moved into derailing position on the rail;

Fig. 2 is an end elevational view, also partly broken away and certain securing spikes being omitted, of the derail illustrated in Fig. 1;

Fig. 3 is a side elevational view of the derail shown in Fig. 1, the securing spikes being omitted;

Fig. 4 is a similar elevational view of the derail with the derail block off the rail;

Fig. 5 is a transverse cross-sectional view through the derail guide box alone, the view being taken along the line 5—5 of Fig. 1;

Fig. 6 is a side elevational view of a derail guide box for a rail supported on level tie plates;

Fig. 7 is a view like Fig. 6 of a derail guide box adapted for a somewhat lower rail;

Fig. 8 is a view like Fig. 7 illustrating a derail guide box adapted for a still lower rail;

Fig. 9 is a side elevational view of a derail guide box constructed with a unitary tie flange and tie plate; and

Fig. 10 is a plan view of one of the unitary tie flange and tie plates utilized in the device illustrated in Fig. 9.

The derail of the present invention is so constructed that it may be adapted for various sizes of rails and for various types of systems, such, for instance, as those wherein the rail is level or canted. It may be constructed readily, as by fabrication, from a number of component parts which are cut or forged or from a number of parts which are cast into the requisite shapes. It comprises but a relatively few parts, as may

be noted from the following description and from the drawings to which reference is now had.

The derail, which is indicated as a whole by reference character 10, is illustrated as being of the sliding type but it should be understood that certain features of the invention may be utilized in the construction of other types of derails, such, for instance, as hinged derails.

The sliding derail illustrated in the drawings includes two main portions. These are a derail block 12 and a derail guide box, indicated as a whole by the reference character 14, upon which the block is slidably mounted. It is to the guide box that the present invention particularly pertains and it is, therefore, contemplated that any desirable or suitable form of derail block may be used.

The illustrated derail block 12 includes a supporting or body section 16 (see Fig. 1) extending to one side from the derailing portion. It is supported on the guide box for what may be termed an up and over movement, i. e., it is movable from a retracted position in which it is illustrated in Fig. 4 to the derailing position in which it is illustrated in Figs. 1 and 3. It is suitably supported in bearings to be described in greater detail hereinafter by a rearwardly extending generally hook shaped portion 18 (see Fig. 2), a pair of intermediate laterally extending bearing members 20 and 22 and a pair of forward main bearings 24, only one of which is illustrated in the drawings (see Figs. 3 and 4). The derail block is also provided with a plurality of downwardly extending lugs 26 near the rear so that suitable operating mechanism may be attached to the derail block to move it. Inasmuch as the operating mechanisms may take various forms, these have not been shown.

The derail guide box includes a pair of vertical side plates 30 and 32, the former being at the left (Fig. 2) and being identical to the one at the right except for the provision of a notch 34 at its upper surface, for a reason to be hereinafter mentioned. The shapes of the vertical side plates may be noted best from Figs. 3, 4 and 5, particularly the latter. The main portions thereof are generally rectangular but the ends adjacent the rail extend generally downwardly and away from the rail. These extensions include a portion 36 of gradual inclination and portion 38 extending nearly vertically.

The derail block supporting and guiding structures are secured to the inner sides of the side plates. These structures are identical, except for one exception, so that only one set will be described, but both sets will be indicated by like reference characters. Referring now more particularly to Fig. 5, it may be seen that these structures include a generally narrow arcuate holding-down shelf 40 secured slightly to the rear of the central portion of the side plate, a seat 42 having a somewhat triangular shaped upper surface and a front pad 44 cut to conform to the configuration of ports 36 and 38 of the forward end of the side plate.

The left holding-down shelf 40 is apertured, as indicated by reference character 45, in the region of the notch 34, for the reception of locking means for the derail block. This locking means may be a padlock (not shown).

The derail block is supported and guided in part by the three pairs of structural elements just referred to. The holding-down shelves 40 cooperate with bearings 20 and 22 to prevent undesired vertical movement of the derail block as it is slid between its two positions; the seats

42 are engaged by the bearing members 24 on the underside of the derail block whereby the derail block is moved vertically as it moves from one position to another; and the pads 44 serve to assist in preventing undesired lateral movement of the derail block. The two positions of the derail block are illustrated in Figs. 3 and 4. In Fig. 3 the derail block is shown in derailing position on top of the rail. At this time the bearing members 24 are at the front sides of the seats 42 while bearings 22 are disposed substantially immediately below the forward ends of the holding-down shelves 40. In the retracted position illustrated in Fig. 4, the bearing members 24 abut against the rear side of the seats and the bearing members 22 are below the rear ends of the holding-down shelves 40. The front end of the derail block is at this time supported by the apices of the seats 42.

The derail guide box comprises a standard shell adaptable to different sizes of rails. It is designed to fit the highest rail of a series of rails without change and may be adapted to fit lower rails by trimming off portions of the side plates 30 and 32 and a front brace 46 shaped with a reversed curve and abutting against the front edges of the side plates. Considered in another manner, the front ends of the side plates and the front brace may be considered as being inclined generally downwardly and away from the web of the rail—the construction constituting a sort of a "nose" fitting underneath the rail head and adjacent the rail web. It is preferred also that the width of the front cross brace be somewhat greater than the distance between the side plates in order that it may be secured, as by welding, to a pair of generally horizontally disposed tie flanges 50 and 52 which are adapted to be secured, as by welding, to the outer sides of the side plates. More will be said shortly about tie flanges and the way in which they are secured to the side plates.

The derail as a whole is supported upon a pair of spaced apart ties 54 by the tie flanges 50 and 52 which are secured to the vertically disposed side plates. The tie flanges are preferably rectangular in shape and are provided with apertures 56 for the reception of spikes 58, by means of which the structure is secured to the ties. The tie flanges have widths preferably corresponding to the projecting portions of the front cross brace 46 so that they may be secured to the brace.

The guide box shell includes also rear cross brace defining structure. This structure includes a curved top brace 60, the downwardly projecting ends of which abut against and are secured to the top edges of the vertical side plates 30 and 32, respectively. The structure includes also a vertically disposed cross brace 62 of generally trapezoidal shape and secured, as by welding, to the ends of the vertical side plates 30 and 32 and the cross brace 60.

The vertical rear cross brace 62 is provided with a bearing 64 adapted to cooperate with the derail block bearing 18. The bearing 64, which is illustrated in Fig. 2, is produced by cutting what may be termed a somewhat L-shaped slot 66 in the lower portion of the vertical cross brace.

Additional rigidity is supplied to the derail by middle side braces 70 and 72 and rear side braces 74 and 76. The middle side braces are generally triangular in shape and are secured to the outer and upper sides of the vertical side plates and horizontal tie flanges, respectively. The rear

side braces constitute, in effect, extensions of the rear cross brace 62 as they are configured to extend from the underside of the latter to the upper surface of the side plates. The rear side braces are secured to the tie flanges, side plates and rear cross brace.

The derail may be readily adapted for either level or canted rail systems. In the instant embodiment of the invention the derail is shown in connection with a canted system. The rail, illustrated by reference character 80, is supported upon tie plates 82 secured in conventional manner to the ties 54 and supporting the rail 80. The tie plates are notched at their inner and adjacent corners, as indicated by reference characters 84 (see Fig. 1) to provide space for the horizontal tie flanges 50 and 52.

The derail guide box is adaptable exactly to fit any height or rail without requiring adzing of the ties under the rail or guide box or without requiring shimming at the same locations. Furthermore, it is adaptable to systems in which the rails are supported on either level or canted tie plates. The adaptability may be noted from a comparison of the embodiment of the invention heretofore described illustrating the guide box adapted to a canted system, with the embodiments of the invention illustrated in Figs. 6, 7 and 8 in which the guide box is shown adapted to a system wherein the rail is supported upon level tie plates. The guide box is quite similar to the one previously described except that the horizontal tie flanges 50 and 52 (like reference characters being used to indicate like parts) are disposed vertically relative to the side plates and the lower ends of the side plates are not only parallel to the tie flanges but are also perpendicular to the side plates and base, as distinguished from being trimmed off at an angle corresponding to the canting.

The derail guide box illustrated in Fig. 6 is of a full height, i. e., it is dimensioned to fit the largest size rail 80A of a series of rails with which the guide box is intended to be used. The side plates 30A, the front cross brace 46A, the middle side braces 70A and the rear side braces 74A have their maximum dimensions.

To adapt the guide box for a rail of lesser height (rail 80B), it is necessary only to trim off portions of the side plates (preferably) and the front cross brace and to use smaller sized middle and rear side braces, as may be noted by comparing the elements 30B, 46B, 70B and 74B of Fig. 7 with the corresponding elements shown in Fig. 6, and to secure the tie flanges 50 and 52 and the braces at the proper positions relative to the side plates.

An adaptation to an even smaller size of rail 80C is illustrated in Fig. 8 and here again the portions of the side plates and front cross brace which are trimmed off are indicated by their respective reference numbers followed by the suffix C.

The derail guide box is also adaptable to different spacing between ties. All that is necessary to adapt it to different spacing is to change the dimensions of the cross brace structure.

Another feature of the present invention is the provision of a derail guide box having unitary tie flanges and tie plates. A guide box of this character is illustrated in Figs. 9 and 10. The guide box structure illustrated in Fig. 9 corresponds to that of the first described embodiment, except for the construction of the unitary tie flanges and tie plates, which are indicated by ref-

erence character 90. It may be noted, particularly from Fig. 9, that the tie flanges are provided with front portions 92 extending underneath and beyond the base of the rail. The rail may be supported either level or canted upon this portion and in the illustrated embodiment it is shown supported in canted position. The canting of the rail is effected by a small pad 94 underneath the outer side of the rail base and having a vertical projection 96 abutting against the rail base to prevent the rail from moving away from the derail. The extensions of the horizontal tie flanges are apertured, as indicated by reference character 98, through which spikes 100 extend in abutting relation with the flanges between to hold the derail in place.

It is readily apparent, therefore, that the derail guide box may readily be adapted to fit any kind of track construction and may be installed with the assurance that it will fit accurately. It is apparent also that when the invention is utilized in conjunction with sliding derails, the movement of the derail block on and off the rail has the same relation to the rail as though both the rail and derail guide box were flat upon the ties.

The derail guide box of the present invention may be readily fabricated from a number of parts which can be cut, forged and welded to form the box. This is the construction employed in the embodiments of the invention described. However, some, or most, of the parts of the guide box may be made as castings and assembled as by welding.

It is contemplated also, to avoid the work required to fabricate the vertical side plates and supporting and guiding structure mounted thereon of steel plate, that these structures may be made of steel castings. Thus the side plates, together with the holding-down shelves 40, the seats 42, and the pads 44, may be made as single steel castings.

It is contemplated also that the derail guide boxes be made from a sub-assembly unit which may be termed "standard shell." This shell includes the vertical side plates and elements secured thereto and the front and rear cross brace structure. This shell may be fabricated or cast as a unit and dimensioned to fit the highest rail of a series of rails without change. The shell can be made to fit lower rails by trimming off portions of the side plates and front brace, after which the horizontal tie flanges are secured to the side plates at proper heights and desired angles to adapt the guide box to any desired track construction.

Other modifications of the present invention will occur to those skilled in the art, and it should be understood that the specific details of the described embodiments are not intended to be limitative of the invention except in so far as set forth in the accompanying claims.

What I claim as new and desire to secure by Letters Patent of the United States is:

1. A derail guide box, including in combination, a pair of spaced apart side plates, a first member secured to and interconnecting said side plates at the front portions thereof, a second member secured to and bridging between said side plates at the rear portion thereof, and means including tie flanges secured to the outer sides of said plates in desired position relative to the plates for supporting said plates and said first and second member on spaced apart ties, and said side plates and said first member being cut

to desired dimensions to adapt the box to a particular height of rail.

2. A derail guide box, including in combination, a pair of spaced apart side plates, a front member secured to and interconnecting said side plates at the front portions thereof, a bridging means secured to and interconnecting said side plates at the rear portions thereof, and tie flanges secured to the outer sides of said plates so that the lower ends of the plates extend a predetermined distance below the flanges, said plates and front member being cut to desired dimensions to adapt the box for a particular height and cant of rail.

3. A derail guide box, including in combination, a pair of spaced apart side plates having their rail web facing ends inclined generally downwardly and away from the rail, tie flanges secured to the outer sides of said plates so that the lower ends of the plates extend below the flanges, a front member secured to the inclined edges of said plates and said tie flanges and interconnecting said side plates, and a rear bridging member secured to and interconnecting the rear portions of said side plates.

4. A derail guide box, including in combination, a pair of spaced apart side plates having their rail web facing ends inclined generally downwardly and away from the rail, tie flanges secured to the outer sides of said plates so that the lower ends of the plates extend below the flanges, a front member secured to said tie flanges and to the inclined edges of and interconnecting said side plates at the front thereof, a bridging means secured to and interconnecting said side plates at the rear thereof, and centrally and rearwardly located side braces secured to said side plates and tie flanges, said rearwardly located side braces effectively constituting a portion of the rear cross brace.

5. A derail guide box, including in combination, a pair of spaced apart side plates having their rail web facing ends inclined generally downwardly and away from the rail, tie flanges secured to the outer sides of said plates so that the lower ends of the plates extend below the flanges, a front member secured to the inclined edges of and interconnecting said side plates at the front thereof, a bridging means secured to and interconnecting said side plates at the rear portions thereof, said side plates and said front member being of generally rectangular shape whereby they may be easily formed with different dimensions to enable the guide box to be used with different height rails or with canted or level rails.

6. A derail guide box, including in combination a pair of spaced apart side plates, a front member secured to and interconnecting said side plates at the front portions thereof, a bridging means secured to and interconnecting said side plates at the rear portions thereof and means including tie flanges secured to the outer sides of said plates in desired position relative to the plates for supporting the plates and structure on spaced apart ties, said side plates and structure being dimensioned to fit the highest rail of a series of rails without change, whereby the lower edges of said plates and said interconnecting member may be cut off to adapt the box for use with lower rails.

7. A derail guide box for a derail having a movable derail block, including in combination, a pair of generally parallel spaced apart side plates, derail block supporting and guiding struc-

ture on said plates, a front member secured to and interconnecting said side plates at the front portions thereof, a bridging means secured to and interconnecting said side plates at the rear portions thereof, and means including tie flanges secured to the sides of said plates at a desired angle for supporting the side plates and structure at said desired angle on spaced apart ties.

8. In a derail guide box for a derail block and adapted to be supported adjacent a rail, the combination of a side plate having substantially plane inner and outer faces, and separately formed derail block supporting and guiding members secured to the inner face of said plate, said members including a seat adapted to coact with a bearing on the derail block to raise the block onto the rail and a holding down shelf adapted to coact with another bearing on the derail block to guide the block during its movement.

9. In a derail guide box for a derail block and adapted to be supported adjacent a rail, the combination of a side plate having substantially plane inner and outer faces, and derail block supporting and guiding members secured to the inner face of said plate, said members being cast as a single unit with said plate and including a seat adapted to coact with a bearing on the derail block to raise the block onto the rail and a holding down shelf adapted to coact with another bearing on the derail block to guide the block during its movement.

10. A derail guide box, including in combination, a pair of spaced apart side plates, a front member secured to and interconnecting said side plates at the front portions thereof, and bridging means secured to and interconnecting said side plates at the rear portions thereof, and means including tie flanges secured to the sides of said plates for supporting the latter on spaced apart ties, said tie flanges including portions extending underneath and beyond the rail for supporting the latter, and the said portions extending beyond the rail being apertured for the reception of securing spikes adapted to bear against the flanges.

11. A derail guide box, including in combination, a pair of spaced apart side plates, a front member secured to and interconnecting said side plates at the front portions thereof, a bridging means secured to and interconnecting said side plates at the rear portions thereof and means including tie flanges secured to the sides of said plates for supporting the latter on spaced apart ties, said tie flanges including portions extending underneath and beyond the rail for supporting the latter, and including upwardly extending structure adapted to support the rail above the flanges and to abut against the outer side of the rail base.

12. A derail guide box, including in combination, a pair of spaced apart side plates, a front member secured to and interconnecting said side plates at the front portions thereof, a bridging means secured to and interconnecting said side plates at the rear portions thereof and means including tie flanges secured to the sides of said plates for supporting the latter on spaced apart ties, and means including unitary tie flanges and tie plates secured in desired position to said side plates for supporting said side plates on spaced apart ties and for supporting a rail.

13. A derail guide box, including in combination, a pair of generally parallel spaced apart side plates, derail block supporting and guiding members secured to the inner faces of said side

plates, a front member secured to and interconnecting said side plates at the front portions thereof, a bridging means secured to and interconnecting said side plates at the rear portions thereof, said bridging means including vertical and generally horizontal members, said last named members being secured together and said vertical member including means for additionally guiding and supporting a derail block, and means including tie flanges secured to the sides of said plates in desired position for supporting said plates, said front member and said bridging means on spaced spaced apart ties.

14. A derail guide box for a derail having a movable derail block, including in combination, a pair of spaced apart side plates, separately formed derail block supporting and guiding structures secured to and carried by said plates, a front member secured to and interconnecting said side plates at the front portions thereof, a bridging means secured to and interconnecting said side plates at the rear portions thereof, said bridging means including a rear derail block supporting and guiding member, and means including tie flanges secured to the sides of said side plates in desired position for supporting said plates and structure on spaced apart ties.

15. A derail guide box for a derail having a movable derail block, including in combination, a pair of spaced apart side plates, separately formed derail block supporting and guiding structure secured to and carried by said plates on the inner sides thereof, a bridging means secured to and interconnecting said side plates at the rear thereof, said bridging means including derail block guiding and supporting means, and means including tie flanges secured to the outer sides of said side plates in desired position for supporting said plates, structure and bridging means on spaced apart ties.

STANLEY W. HAYES.
